CLAIM

The ornamental design for handle for firearm maintenance, as shown and described.

DESCRIPTION

FIG. 1 is a perspective view from above of a handle for firearm maintenance, showing our new design;

FIG. 2 is a perspective view from below thereof;

FIG. 3 is a top view thereof, the bottom view (not shown) being the same as the top view;

FIG. 4 is a left view thereof, the right view (not shown) being the same as the left view;

FIG. 5 is a front end view thereof; and,

FIG. 6 is a back end view thereof.

The broken lines in the drawings disclose unclaimed portions of the handle for firearm maintenance only and form no part of the claimed design.
